FRANZ KRATZ, OF STUTTGART, GERMANY, ASSIGNOR, BY KESSELE ASSIGNMENTS, TO
AMERICAN BOSCH MAGNETO CORPORATION, OF NEW YORK, N. Y., A CORPORATION
OF NEW YORK.

STARTING APPARATUS FOR INTERNAL-COMBUSTION ENGINES.

1,383,311.

Specification of Letters Patent. Patented July 5, 1921.

Application filed April 8, 1918. Serial No. 23,162.

To all whom it may concern:

Be it known that I, FRANZ KRATZ, a subject of the Emperor of Germany, residing at and whose post-office address is Schlossstrasse 59a, Stuttgart, Germany, have invented certain new and useful Improvements in Starting Apparatus for Internal-Combustion Engines; and I do hereby declare the following to be a full, clear, and exact description of the invention, such as will enable others skilled in the art to which it applies to make and use the same.

The present invention relates to starting apparatus for internal combustion engines, and particularly to apparatus in which a combined starting and running ignition system is provided for an engine having a starting motor, wherein the controlling member not only connects the source of power supply to the motor to start the engine, but simultaneously renders the ignition system effective to produce satisfactory ignition currents at the spark plugs of the engine during the starting period. Subsequently 25 the controlling member disconnects the source from the starting motor and renders the buzzer ineffective in its reverse operation.

It was customary heretofore to provide in such systems independent starting and running ignition apparatus. In accordance with my invention, a magneto is geared to the engine for producing the ignition currents during running, and the starting ignition apparatus, comprising a buzzer or other electromagnetic vibrator, is utilized to supply vibratory currents to the magneto for producing ignition currents during the starting period. In this way, the starting ignition apparatus is simplified in that the service magneto performs, during the starting period, the function of a secondary winding for the buzzer, whereas, if desired, the mechanical interrupter of the magneto may time the ignition currents produced thereby, and the distributor of the magneto may distribute the ignition currents to the engine cylinders in turn in the case of a multicylinder engine. By utilizing this arrangement in a system in which the buzzer is rendered effective for supplying vibratory currents to the magneto at the same time the source of power supply is connected to

the starting motor, the engine is brought into operation under its own power at a comparatively low speed, and thereafter the magneto alone supplies the ignition currents to the engine during the running thereof.

The idea as disclosed herein may be applied to various kinds of starting motors, such as electric, compressed air or spring, and to various kinds of starting ignition systems. As an example, I describe herein-after starting apparatus wherein an electric starting motor and battery are employed and wherein the starting ignition apparatus embodies a high frequency interrupter supplied with current by the battery and discharging into the primary winding of the engine driven magneto to generate in the secondary winding thereof ignition sparks which are effective for the purpose irrespective of the speed of rotation of the magneto. In the accompanying diagrammatic drawings, Figures 1 and 2 show a four cylinder engine, as an example, and similar starting apparatus excepting the switching arrangement therefor.

In both modifications, the starting motor *a* drives the crank shaft of the engine *w* through suitable gearing, and the magneto *f*, mechanical interrupter *x* and distributor *t* are geared to the engine in the well known way. The magneto has a primary winding *g*, one end being grounded and the other end being connected to one end of the secondary winding *i* and also to the insulated and fixed contact *h* which co-operates with the grounded deflecting contact lever *m* of the mechanical interrupter. The other end of the secondary winding *i* is connected to the collector ring and thence through the brush *k* to the rotatable brush of the distributor *t*, from whence the high tension ignition currents are distributed to the spark plugs in the engine cylinders. The starting ignition apparatus comprises a high frequency interrupter or buzzer having one end of its winding *n* connected by means of a brush to the interrupter contact *h*, and having its other end connected to the vibrating armature *o* which co-operates with the contact terminal *p*.

In both modifications the switching apparatus connects the battery *b* to the starting motor *a* for driving the engine, and

simultaneously connects the battery b to the interrupter n, o for producing ignition sparks at the spark plugs during starting. However, according to Fig. 1, the electro- 5 magnetically operated switch, having the winding e and the switch bridge c , closes the circuit from the battery b to the starting motor a and also closes the circuit at r, s from the battery b to the interrupter n, o , whereas, according to Fig. 2, the hand operated switch d closes the coöperative contacts r, s in the circuit between the battery b and the interrupter n, o , while the electromagnetically operated switch connects the bat- 10 tery to the starting motor. In both cases the winding e is connected to the battery b by the hand operated switch d , and in Fig. 2 the arrangement is such that the contacts r, s are closed and opened at the same time that the circuit of the winding e is closed and opened. In Fig. 1 the insulating block t is interposed between the switch bridge c and the spring-supported contact s , the arrangement being such that the coöperative contacts r, s close and open the circuit from the battery b to the interrupter n, o at the same time that the switch bridge c closes and opens the circuit from the battery b to the starting motor a .

It will now be understood that a single operation of the switch d puts the normally inactive starting motor a and interrupter n, o into operation, causing the starting motor to drive the engine w and simultaneously 30 causing ignition voltages suitable for producing effective ignition sparks at the spark plugs to be generated in the secondary winding of the magneto f . In this way, ignition voltages, whose spark-producing effectiveness is independent of the speed of the engine, occur at the spark plugs during the entire starting period, causing the engine to start under its own power as soon as the combustible mixtures in the cylinders have sufficient richness to produce a sufficient impulse intensity at sufficient frequency. Thus, besides simplifying the duty of the operator, the critical speed of the engine is less than the speed at which the engine will 40 otherwise start, because the critical speed is less than that at which the magneto f ordinarily produces effective ignition sparks due to rotation. The critical speed being less, the size of the starting motor a and of the battery b is less, and thus the weight and space requirements of the starting equipment may be appreciably reduced.

Furthermore, the switching arrangement is such that the reverse operation of the 60 switch d disconnects the current supply from the starting motor and the starting ignition apparatus, thus discontinuing the driving effect of the starting motor and also rendering the starting ignition system inactive, so that the starting equipment is ready 65 at all times thereafter to be put into action merely by again closing the switch d . By connecting the interrupter n, o to the insulated contact h of the mechanical interrupter, ignition sparks can occur at the 70 spark plugs only at the periods of separation of the contacts m and h , and in this way premature ignition during the starting period is avoided.

Having thus described my invention, 75 what I claim is:

1. The combination with an internal combustion engine having spark plugs, and a starting motor for the engine; of a combined starting and running ignition system comprising a magneto geared to the engine for supplying ignition currents to the spark plugs during the running period; a buzzer connected to the magneto to supply vibratory currents thereto; a source of power supply; and a controlling member, which in a single operation, connects the source to the motor to start the engine and renders the buzzer effective to cause the magneto to supply ignition currents to the spark plugs during the starting period, and which, in the reverse operation, disconnects the source from the motor and renders the buzzer ineffective so that the magneto by itself supplies the ignition currents to the spark plugs. 85

2. The combination with an internal combustion engine having spark plugs, and a starting motor for the engine; of a combined starting and running ignition system comprising a magneto geared to the engine for 100 supplying ignition currents to the spark plugs during the running period; a buzzer connected to the magneto to supply vibratory currents thereto; a source of power supply; an electromagnetically-operated controlling member; and a hand-operated switch which, in a single operation, causes the electromagnetically-operated controlling member to connect the source to the motor to start the engine and to the buzzer to render it effective to supply vibratory currents to the magneto for producing ignition currents therein during the starting period, and which, in the reverse operation, disconnects the source from the starting motor and the 105 buzzer so that the magneto by itself supplies the ignition currents to the spark plugs. 110

In testimony whereof I affix my signature, in presence of two witnesses.

FRANZ KRATZ.
